UNITED STATES PATENT OFFICE.

IRENE HODGES, OF SAN FRANCISCO, CALIFORNIA.

RAISING AND LOWERING MECHANISM FOR CURTAINS.

1,102,921.

Specification of Letters Patent.

Patented July 7, 1914.

Application filed January 14, 1914. Serial No. 812,078.

To all whom it may concern:

Be it known that I, IRENE HODGES, a citizen of the United States, residing at San Francisco, in the county of San Francisco and State of California, have invented new and useful Improvements in Raising and Lowering Mechanism for Curtains, of which the following is a specification.

This invention relates to raising and lowering mechanism for theater curtains, window shades or the like; and it has for its primary object the provision of electrically controlled mechanism for winding the curtain on or unwinding the same from its supporting roll and for automatically retarding the rotation of the roll instantly on the requisite adjustment of the curtain.

With the above and other objects in view, the invention consists of certain novel features of construction, combination and arrangement of parts, as will be hereinafter described and claimed.

In the accompanying drawings:—Figure 1 is a front view of the curtain conventionally showing the application of the winding and unwinding mechanism thereto; Fig. 2 is a side view of the controlling motor; Fig. 3 is a section, taken on line 3—3 of Fig. 2; Fig. 4 is a front view of the strip; Fig. 5 is a side view thereof; and Fig. 6 is a diagrammatic view, illustrating the manner of connecting the motor respectively in the armature and field circuits.

As specified the mechanism is primarily intended for raising and lowering theater curtains, window shades or the like and conventionally illustrated in Fig. 1 a supporting roll A is mounted to revolve in brackets B that are mounted above the opening C over which the curtain D is adapted to be extended. The axis or shaft 1 of the roll A is connected at 2 with a motor 3, and as illustrated in Fig. 6 said motor is connected in a field circuit E and an armature circuit F, the armature being conventionally illustrated at G while the field magnets are shown at H. Contact posts I—I are connected with the terminals of the field circuit, and as shown these posts are associated with similar posts J—J of a switch K, the latter being clearly illustrated in Figs. 4 and 5. The said posts J are connected through the leads K'—K' with the field circuit E, while connected through the armature circuit are posts L—L, on which

switch blades M—M are secured, as at N. These blades are preferably disposed in parallel relation and they are adapted to extend over the posts I—I and J—J and to be spaced therefrom normally, as shown in Fig. 5. For this reason the blades M—M are constructed preferably of strips of flat sheet spring metal that are adapted to normally be in flat condition but which are adapted to be flexed at their ends so as to be thrown respectively into engagement with the contacts I—I and J—J. The said strips M—M are connected with each other by insulating blocks O—O, which are provided intermediate of their ends with handles P. In the circuit E is a solenoid 4, the core 5 thereof being normally held in an extended position by means of a spring 6. This core is connected at 7 to links 8, and in turn these links are pivoted to rocking brake levers 9 that terminate in brake shoes 10 having concavities 11 which accommodate the peripheral surface of a friction wheel 12 mounted on the motor axis 2.

With particular reference to Figs. 4, 5 and 6 of the drawings it will be seen by the manual depression of the switch K by the lower handle P the blades M will be moved into engagement with the contacts I—I, closing the electric circuit and causing the current to be taken from the main line and conveyed to the field circuit and through the solenoid so as to energize the same and through the armature circuit so that the brake shoes 10 will be released from the friction wheel 12 and the shaft 1 revolved to cause an unwinding of the curtain as will be understood. The contacts J—J are reversely connected to the field circuit with respect to the contacts I—I, so a depression at the opposite handle P of the switch K, bringing the same into engagement with the contacts J—J, thus reverses the direction of the current through the field and, as a consequence, the curtain will be drawn onto the roll. Immediately on moving the switch to an open circuit position, the solenoid will be influenced under the action of the springs 6 and the brake shoes 10 will be instantly moved to applied position. The circuit F may be provided with an ordinary switch S to cut off the circuit from the main line or to direct the circuit therethrough as desired.

From the foregoing description, taken in connection with the accompanying drawings,

the construction and operation of the invention will be readily understood without requiring a more extended description.

Various changes in the form, proportion and the minor details of construction may be resorted to without departing from the principle or sacrificing any of the advantages of this invention as claimed.

I claim:—

- 19 1. The combination with a revolvably mounted roll and a curtain wound thereon, of electrically controlled means for respectively winding and unwinding the curtain, and means automatically operated on adjustment of the curtain to a predetermined position for holding the supporting roll thereof against rotation and comprising means actuated directly through the said electric circuit.
- 20 2. The combination with a revolvably mounted roll and a curtain wound thereon, of electrically controlled means for respectively winding and unwinding the curtain, and means automatically operated on adjustment of the curtain to a predetermined position for holding the supporting roll

thereof against rotation and comprising means actuated directly through the said electric circuit having normally active shoes engaging the axis of the roll and movable to inactive positions on closing the circuit.

3. The combination with a revolving roll having a curtain wound thereon, of electrically operated means for respectively winding the curtain onto and off of the roll and 35 consisting of a motor connected with the roll, an electric circuit connected with the motor, means for determining the direction of movement of the current through the circuit to cause the curtain to be respectively wound 40 onto and unwound from said roll, and a solenoid in the circuit, a brake wheel on the axis of the motor and shoes coöperating with the wheel and controlled through the solenoid.

In testimony whereof I affix my signature in presence of two witnesses.

IRENE HODGES.
